UNITED STATES PATENT OFFICE.

FRANK O. NITCH, OF CLEVELAND, OHIO.

BOILER CLEANER.

Application filed November 12, 1918. Serial No. 262,149.

To all whom it may concern:

Be it known that I, FRANK O. NITCH, a citizen of the United States, residing at Cleveland, in the county of Cuyahoga and State of Ohio, have invented a certain new and useful Improvement in Boiler Cleaners, of which the following is a full, clear, and exact description, reference being had to the accompanying drawings.

10 This invention relates to a boiler cleaner or skimmer of that type wherein there are floating mouth pieces maintained at the surface of the boiling water and connected with a suitable conduit so that the opening 15 of the discharge valve from the conduit may enable the pressure within the boiler to discharge the scum or other impurities from the surface of the water. The general object of the invention is to simplify and improve 20 the floating structure and enable the mouth- pieces to receive scum from a large area of surface and effectively discharge it. One of the difficulties in prior constructions of this type has been that the device would 25 not force scum evenly from all parts of the surface but would discharge through one mouthpiece more or less to the exclusion of the others. My invention has been de- 30 signed after a large amount of experiment- ing with a view to effecting an even dis- charge over substantially the entire surface 35 of the boiler water. The invention is here-inafter more fully explained in connection with the drawings and its essential char- acteristics are summarized in the claims.

In the drawings Fig. 1 is a side elevation of the upper portion of a boiler, partly broken away, showing my skimming attachment; Fig. 2 is a plan of the skimming attachment; Fig. 3 is a vertical transverse section of the skimming attachment looking toward the free end; Fig. 4 is a detail illustrating the tubular hinge connection in the exit pipe; Fig. 5 is a perspective of one 45 of the mouthpieces; Fig. 6 is a vertical section through the intermediate mouthpiece and an attached tubular brace.

In the drawings, 1 indicates the shell of the boiler; 2 the tubular body of the float- 50 ing structure; 3 the mouthpieces; 4 the floats supporting the same; 5 the movable exit pipe leading from the floating structure and having a swiveled and hinged con- nection therewith, and 6 the external dis- 55 charge pipe extending into the boiler and having a hinged connection with the other

end of the exit pipe 5. The external pipe 6 is provided with a blow-off valve 7, which may be opened to discharge scum whenever desired. The specific construction shown 60 will now be more fully described.

The floating structure comprises a set of intake mouthpieces 3, individual tubes 2 connected therewith, and a header 10 into which the tubes extend. Each mouth piece is a 65 flattened funnel having as its intake opening a slot 11 extending longitudinally of the floating structure. The lower end of each funnel is formed into an elbow 12 connected with the corresponding tube. I have 70 shown three of the funnel intakes, each connected with an individual tube leading to the hollow header.

To effectively support the tubular body mentioned and allow it to float on the surface of the water and tip in any direction as the water surges, I arrange the floats 4 in pairs, one member of each pair being on one side of the set of tubes and the other member on the other side. These floats are 80 suitably connected to blocks 15 clamped to the pipe. As shown each block has a pair of holes for the passage of two tubes and is provided with a pair of set screws 16 for clamping the blocks to 85 the tubes. Beneath the tube the block has a transverse bore into which extends studs 17 projecting from disk like members 18 se- cured to the floats 4. The bore referred to is preferably internally threaded and the 90 studs screwed into such threaded bore are locked by suitable means, as by jam nuts 19.

To rigidly brace the extreme portion of the floating structure where there is only one tube 2, I provide a tube or rod 20 which 95 is brazed to the elbow of the intermediate mouthpiece 3 and at its other end is connected with the end block 21. The function of this bracing tube is to properly stiffen the end portion of the structure and supply 100 a proper support from the extreme pair of floats. The floats may be positioned as de- sired lengthwise of the tubes by adjusting the blocks thereon.

The header 10 into which the various tubes 105 of the body portion extend is connected by a swiveled hinged and movable tubular con- nection with the external discharge pipe 6. To this end I have shown an intermediate exit pipe 5 having at 110 one end a hinged and swiveled con- nection with the floating structure and at

the other end a hinged connection with the discharge pipe. The hinged connections are preferably made by means of two elbows 24 racing each other and held together by a bolt 25 passing through them. One elbow has a reduced extension 2 extending into the other as illustrated in Fig. 4. The plane of separation of the elbows is vertical so that the pipe 5 may swing in a vertical plane about its outer end and the floating body may swing also in a vertical plane about the inner end of this movable exit tube.

The connection described enables the body to rise and fall with the varying water level. Tipping of the body about a transverse axis as the water surges is also allowed by the hinging at the inner end of the exit pipe 5. Tipping about a longitudinal axis is allowed by reason of the swiveling of the header in the elbow connection on the exit pipe. This swiveling is shown as accomplished by means of an extension on the header projecting into the elbow, a suitable set screw 26 in the elbow 25 projecting into a groove in the reduced extension prevents separation of the parts while allowing the header body to tip axially with reference to the elbow.

To prevent injury to the floats by reason of their striking against the boiler shell, I provide a pair of bumper loops 30 which are secured to the end block 21 of the floating structure and lie in a vertical transverse plane.

It will be seen that the floating device is simple in construction, being readily made and assembled, that there is nothing about it to get out of place in use. The mouth pieces extend a sufficient distance above the tubular body so that the floats maintain them just below the surface of the water. By providing each mouth piece with its own tube leading to the common header I enable the scum to be effectively forced through all the mouthpieces. The combined area of the several entrance openings in the mouth pieces is approximately equivalent to the cross sections of the common discharge conduit. Experience with my skimmer has demonstrated that the flow of liquid through the common exit tube receives its supply through all the mouth pieces and the scum is forced from substantially the entire surface of the boiling water.

Having thus described my invention what I claim is:

1. In a device of the character described, the combination with a set of tubes located side by side, of a vertically disposed mouthpiece connected with each tube, the upper end of each mouthpiece having a narrow slot and the lower end having an elbow connected with one end of the corresponding tube, a header to which the

other end of each tube is connected, a discharge conduit having a swivel connection with said header, and floats secured to the set of tubes on opposite sides thereof.

2. In a device of the character described, the combination with a set of parallel tubes of a header to which the end of each tube is connected, a common exit pipe swivelly connected with said header, an upwardly extending mouthpiece carried by each tube, each mouthpiece having a narrow slot positioned parallel to the associated tube and disposed in a horizontal plane, members extending across the tubes and rigidly attached thereto, and floats carried by said members and on opposite sides thereof respectively.

3. The combination with a set of longitudinal tubes side by side and a mouth piece for each tube consisting of a flattened funnel having a longitudinal entrance slot at its top and an elbow at its lower end connected with the end of a tube, a header with which the various tubes are connected, a plurality of separated floats supporting the structure mentioned at each side of said set of tubes, and a discharge pipe having at its inner end a pair of elbows swiveled together on a transverse axis and a swivel connection between one of said elbows and the header on a longitudinal axis.

4. In a device of the character described, the combination with individual mouth pieces, of a set of parallel longitudinal tubes located side by side and connected with the mouth pieces, a discharge conduit connected with the tubes, a swivel connection associated with the conduit, said connection having a cross sectional area at least equal to the sum of the cross sectional areas of the individual tubes, transverse blocks embracing the tubes, and floats secured to the blocks on opposite sides thereof.

5. In a device of the character described, the combination of a set of tubes side by side, a header to which one end of each tube is connected, an exit pipe having a swivel connection with the header, blocks engaging the tubes, floats on opposite sides of the tubes, and heads for the floats secured to said blocks.

6. The combination with parallel tubes side by side, a discharge conduit with which the tubes are connected at one end, transverse blocks embracing a plurality of the tubes, floats secured to the blocks, individual mouth pieces in the form of flattened funnels having elbows connected with the ends of the respective tubes.

7. The combination of a header, a discharge pipe to which it is pivotally connected, a set of parallel longitudinal tubes communicating with the header, upwardly

extending funnel shaped mouth pieces secured to the other ends of the respective tubes, transverse blocks embracing a plurality of tubes, floats on the opposite sides 5 of the blocks, and means securing the floats to the blocks.

8. The combination of a tubular body having mouth pieces and connected with the discharge conduit, floats on opposite 10 sides of the body for supporting it and a pair of bumpers in the form of loops larger than the outside of the floats and in longitudinal alignment therewith carried with the body for protecting the floats.

15 9. The combination of a movable discharge pipe, of a header swiveled thereto, a tubular body connected with the header, a block carried by the body at its other end, a pair of wire bumper loops carried 20 by the block, mouth pieces for the body,

and supporting floats on opposite sides thereof.

10. The combination of a stationary discharge pipe, of a movable exit pipe within the boiler having a hinge connected with 25 the discharge pipe, a floating tubular body having a hinged connection with said exit pipe, and comprising a set of parallel tubes terminating in a header which is swivelly connected with the inner end of the exit 30 pipe, each tube being provided with an upwardly extending intake mouth piece, a block at the farther end of the tubes, bumpers carried by the block and pairs of floats individually on opposite sides of the 35 tubular body connected therewith between said header and said end block.

In testimony whereof, I hereunto affix my signature.

FRANK O. NITCH.
